[57] **CLAIM**

The ornamental design for a propane fired heater for defrosting frozen pipes or the like, as shown.

DESCRIPTION

FIG. 1 is a top, front, and left side perspective view of a propane fired heater for defrosting frozen pipes or the like, showing our new design;

FIG. 2 is a top plan view thereof on a reduced scale; FIG. 3 is a right side elevation view thereof on a reduced scale;

FIG. 4 is a front elevation view thereof on a reduced scale;

FIG. 5 is a left side elevation view thereof on a reduced scale;

FIG. 6 is a rear elevation view thereof on a reduced scale; and

FIG. 7 is a bottom plan view thereof on a reduced scale.

FIG. 1

FIG. 2FIG. 5FIG. 4FIG. 3FIG. 6

FIG. 7
